UNITED STATES PATENT OFFICE.

ROY H. GERARD, OF DETROIT, MICHIGAN, ASSIGNOR TO MORGAN & WRIGHT, A CORPORATION OF MICHIGAN.

MIXING MACHINE.

1,418,641.

Specification of Letters Patent. Patented June 6, 1922.

Application filed May 25, 1921. Serial No. 472,382.

To all whom it may concern:

Be it known that I, ROY H. GERARD, a citizen of the United States, residing at Detroit, in the county of Wayne and State of Michigan, have invented certain new and useful Improvements in Mixing Machines, of which the following is a full, clear, and exact description.

This invention relates to mixing machines in general and in particular to a type thereof for compounding rubber and various ingredients into a batch suitable for spreading, calendering, tubing or other like operations incidental to the manufacture of vulcanized articles. The old practice was to prepare a batch on a mill consisting of co-operating rollers, powerfully driven, which squeezed and worked the mass into a more or less homogeneous condition. An operator was required to attend the mill and the thoroughness of mix depended in large measure upon his individual skill.

The present invention relates to a mechanical mixer requiring no attention after charging, which is much more rapid than the old mixing mill. Mechanical mixing machines of various forms have been proposed heretofore and this invention aims to provide new and improved features rendering the machines more practical for manufacturers.

Briefly, it consists in a tub or container in which rotate agitators and about the axis of one of which agitators, the container or tub may be tilted for convenience in discharging a properly prepared batch without stopping the rotation of the agitators. A combined cover and hopper is movably supported at the top of the container or tub for convenient charging of the materials and for convenient removal to a non-obstructing position when the container is tilted to discharge a prepared batch.

The invention is illustrated in the accompanying drawings in which:—

Fig. 1 is an elevation partly in section of a preferred embodiment of the invention.

Fig. 2 is a plan view of the same also partly in section,

Fig. 3 is an elevation of the machine 50 viewed from the side opposite Fig. 1.

In the drawings the container or tub is indicated at 1 and as shown has a partition or rib 2 dividing it into communicating cylindrical chambers 3 and 4, respectively, in each of which is an agitator 5. These may be of any suitable form, preferably hollow as shown, and lengthwise curved or shaped in any of the ways disclosed in the patents of the prior art, such, for instance, as Mosher No. 1,371,046, March 8th, 1921. The tub 1 is preferably, but not necessarily, also hollowed out or jacketed as indicated at 6 for circulation therethrough of a heating or cooling medium, such as water or steam. The temperature of the hollow agitators 5 may be likewise governed.

The container 1 is tiltably supported on the driving shaft 7 of one of the agitators 5, this shaft being journaled in relatively heavy side frames 8 and on its opposite ends being provided with a bull-gear 9 and a pinion 10, the former adapted to be driven in any suitable manner as by a pinion 11 from a suitable source of power such as a line shaft or motor, and the latter, through the gear 12, driving the shaft 7 on which the second of the two agitators 5 is mounted. On each side of the container 1, and disposed vertically, are formed mutilated gears 13 which mesh with racks 14 mounted in guides 15 and loosely pinned as indicated at 16 to the plunger 17 of a horizontally arranged fluid pressure cylinder 18 that is suitably fixed to the frame of the machine. By operation of the plunger 17, the container 1 may be swung from the position shown in Fig. 1 to the tilted discharging position shown in Fig. 3 determined by stops 18' and without interruption of the drive of the agitators 5.

The container 1 is closed by a combined cover and hopper, the former portion being indicated by the numeral 19 and the latter portion being indicated by the numeral 20, Fig. 1. The combined cover and hopper 19-20 is pivoted as indicated at 21 to the free ends of spaced arms 22 which together

constitute a lifting lever that is fulcrumed at 23 to plates or brackets 24 integral (or otherwise made rigid) with the end walls of the container 1. Between the plates or brackets 24, a second fluid pressure cylinder 25 is suitably fixed for operation of a plunger 26 that is yieldably connected, by coiled springs 27 and a sleeve 28 slidable on the plunger rod, to trunnion pins 29 that are loosely received by the lever arms 22. As will be obvious, operation of the plunger 26 will move the lever arms 22 about the fulcrum 23 and lift the combined cover and hopper 19-20 away from the container 1.

To impart, in addition to the above mentioned lifting movement, a turning movement to the combined cover and hopper 19-20 about the pin 21 as a center, links 30 are hinged thereto as indicated at 31, these links being also loosely pinned as indicated at 32 to upstanding bracket pieces 33, which latter are integral with the plates or brackets 24 and therefore also fixed relative to the container 1. Consequently, lifting the lever 22 not only lifts the combined cover and hopper 19-20 but also turns the latter as indicated in dotted lines in Fig. 1.

Preferably, but not necessarily, the hopper portion 20 is closed by a shutter 34 hinged to a hand-lever 35 that is fulcrumed as indicated at 36 to the combined cover and hopper 19-20, suitable play or enlargement being provided at the opening 37, where the shutter passes through a wall of the hopper, to permit the incidental free movement that is necessary.

In operation, the agitators 5 are continuously driven. Supposing container 1 to be empty, material is charged into the hopper portion 20 and the shutter 34 retracted by suitable movement of the hand-lever 35. The rubber, sulphur and other ingredients that have been previously gathered in the desired proportions are then introduced and fall within the range of action of the agitators 5 by which they are vigorously worked and blended into a homogeneous mass. Without stopping the agitators, and at the completion of the mix, the container 1 is swung to the tilted position shown in Fig. 3, this being done by suitable operation of the cylinder 18. Then the combined cover and hopper 19-20 is swung to a clear or non-obstructing position and the mixed batch discharged. Preferably, the batch is discharged into a bucket 38 that rests on a conveyor or gravity run-way 39 having rollers 40. The container or tub 1 is then restored to its normal horizontal position ready for recharging and another cycle of operations.

From the foregoing description it will be seen that I have provided a simple, compact and readily operable device for mixing up batches of rubber composition. Its overall

height is relatively small, for an average size machine the mouth of the charging hopper need not be more than three or four feet above the floor. The tilting of the container is accomplished by simple operation of a hydraulic cylinder as is also the opening of the mouth of the container. By the arrangement of the fulcrum 23 for the lever carrying or supporting the combined cover and hopper at substantially the same elevation as the mouth of the container, no great amount of head-room is required above the machine as heretofore seems to have been the case. The yielding driving connection 27-28 between the cylinder 25 and the lever 22 permits the necessary power operation of the combined cover and hopper and also insures against breakage in case of jam from charging of the container beyond its capacity.

Having thus described my invention what I claim and desire to protect by Letters Patent is:

1. A mixing machine including in combination, a container, agitating means within the container, means for actuating the agitating means, a combined cover and hopper for completely confining material in the container, means for tilting the container to discharge its contents, and means including a lever movable about a fulcrum fixed relative to the container for removing the combined cover and hopper from a position obstructing discharge of the contents of the container.

2. In a mixing machine, a container, agitating means within the container, in combination with a combined cover and hopper for completely closing the container, a lever fulcrumed at one side of the container and articulated to said combined cover and hopper, and means for operating said lever to lift the combined cover and hopper and open the container.

3. In a mixing machine, a container, agitating means within the container, in combination with a combined cover and hopper for completely closing the container, a lever loosely pinned to the latter and fulcrumed at one side of the container, a link loosely connected at one end to the combined cover and hopper and at its other end hinged in spaced relation from the fulcrum of said lever, and means for operating said lever to lift and turn the combined cover and hopper.

4. In a mixing machine, a tiltable container, agitating means revolvable within the container, a combined cover and hopper for completely closing the container, articulated supporting and actuating connections for said combined cover and hopper, and separate fluid pressure devices for moving said connections and thereby the combined cover and hopper and for tilting the container.

5. In a mixing machine, a container, agitating means within the container, in combination with a combined cover and hopper for completely closing the container, a lever 5 fulcrumed at one side of the container, a link loosely connected at one end to the combined cover and hopper and at its other end hinged in spaced relation from the ful-

crum of said lever, means for operating said lever to lift and turn the combined cover 10 and hopper, and a yielding actuating connection between said lever and its operating means.

Signed at Detroit Michigan this 14th day of May 1921.

ROY H. GERARD.
